UNITED STATES PATENT OFFICE.

MARIO AUGUSTO CANALE AND RICARDO FRIAS, OF BUENOS AIRES, ARGENTINA.

DEVICE UTILIZING THE TREPIDATIONS OF VEHICLES.

Application filed April 23, 1921. Serial No. 463,925.

To all whom it may concern:

Be it known that we, MARIO AUGUSTO CANALE and RICARDO FRIAS, both citizens of the Argentine Republic, residing at Calle 5 Maipu 671, Buenos Aires, Argentine Republic, have invented new and useful Improvements in a Device Utilizing the Trepidations of Vehicles, of which the following is a specification.

10 This invention relates to a device intended to be placed on street cars, railway cars or similar vehicles and wherein the trepidations or other displacements or movements in any direction of the running vehicle are used

15 to automatically move an advertising or displaying tape or any other device which is to be continually or intermittently moved or fed along.

As will hereinafter be seen, the apparatus 20 substantially consists of one or several weights, held in position by a corresponding number of steel springs and conveniently combined by means of a pawl and ratchet wheel. By this arrangement, any sudden 25 displacement of the centre in which the springs are mounted, will cause the same to oscillate under the action of the weights gravitating thereon until returned again to the original position, the equilibrium of 30 which was disturbed by the displacement.

It will be evident that as the vehicle is running, either on rails or otherwise, more or less considerable displacements or vibrations will occur at every moment and in consequence 35 the weights, owing to the particular manner in which they are arranged, will continuously be caused to oscillate. The springs which support said weights, by operating after the manner of levers, will impart a rotary motion to the toothed wheel from which, motion, may be transmitted by means of any usual gear, to the device to be operated.

For the better understanding of this description, illustrative drawings have been 40 annexed thereto, wherein:—

Figure 1 shows a front elevation, partially in section, of an advertising device, automatically operated by the apparatus in accordance with this invention.

50 Figure 2 is a plan view of the oscillatory operating device, shown with the tape removed therefrom.

Figure 3 illustrates a lateral elevation of the device.

55 In said drawings, 1 indicates a central

block or bracket wherein by means of the screws 2 are securely mounted the springs 3, to the free ends of which are secured the oscillatory weights 4. To each of said springs is conveniently secured a tooth 5 which operates on a toothed wheel 6. This latter rotates on a centre 7 and is provided with a bevel gear 8, in engagement with a pinion of similar shape 9. This pinion is mounted on the axle 11 of a counterweighted arm 10 and when rotated by the rotation of pinion 9 operates by means of the axle 11 the wheel provided with lateral teeth 12. The arm 10 carries a cross arm 13 through which the end 17 of lever 18 projects and has a protruding central part, to form the notches 14 at either side of the protruding part into which notches respectively the pressure roller 15 urged by the spring 16 fits when arm 10 is moved to corresponding position by 60 the end 17 of the lever 18 which oscillates on a fulcrum 19, being counterbalanced by a suitable contracting spring. The lever 18 is provided with a projection having notches 70 20 with which engages the pressure roller 80 21 under the action of the spring 22, for the purpose of holding the said lever engaged in the position required. Said lever 18 is movable in a guide sector 23 and carries at its end a projection 24 with which engages 85 flanges or flaps 25, arranged in opposite directions, one on each end of the advertising tape 26. By this means, when the tape reaches the flap in its circulatory travel, in one direction, the flap at this point becomes 90 engaged with the projection 24 and causes the lever 18 to travel through half a stroke, after which, under the action of the spring 22, it will assume its definite position, that is to say, with reference to Figure 2, it 95 will be carried from the position A to the position B and vice versa.

The movement of the lever 18, on account of being combined with that of the cross arm 13, moves the arm 10 so as to cause the 100 gear 12 to engage with one or the other of the pinions 27 and 28, mounted on their respective axles 29 and 30, and thereby impart motion to the bevel gears 31 and 32. The rollers 33 and 34 on which is wound the 105 advertising tape 26, carry on one of their ends a bevel pinion 35 and 36, respectively, while the opposite end is formed by a simple pivot. For the purpose of facilitating the insertion and withdrawal of said rollers, 110

the bearings 37 and 38 are constructed of two parts, one of them, 39, being operated upon by a spring 40 so as to cause the same to join the other part. By means of this arrangement, when one roller is operated for winding the tape, the other is allowed to rotate freely.

The parts of the oscillatory apparatus are enclosed within a casing, on whose cover 41 10 is secured by one of its ends, a spring 42 which permits of stopping at will the oscillatory movement of the weights 4, or, what is the same, the operation of the apparatus. For that purpose, the spring 42 is connected 15 by means of the link 43, to the arm 44, held in one position or the other by means of the spring 45, being operated by means of the rod 46 which projects outside the casing 47 which contains the parts of the machine. 20 The casing may be made of any suitable material and size, and its outer ornamentation may be varied as desired. In any event, the front part or wall thereof formed by a hinged door, consists of a frame with a 25 window pane 48 through which is fully displayed the advertising tape.

The operation of the apparatus is as follows:—

The casing having been secured in position 30 at any suitable place of the vehicle, any movement transverse to the direction of travel of the same, will bring about within the casing the oscillation of the weights 4, said oscillations being greatest with regard 35 to the weight whose spring 3 occupies the position most nearly perpendicular in relation to the direction of motion.

It will be readily understood that no matter how fine be the conditions of the pavement or rails, there will always exist some slight unevennesses which will cause in the car or other vehicle trepidations which in turn will be sufficient to cause the operation of the device.

45 The oscillation of the weights 4 will cause the teeth 5 to impart a rotary motion to the wheels 6 and 8, which latter will transmit said movement, through its engagement with the pinion 9, to the wheel 12. According to 50 the position of the beam or arm 10, said wheel will engage with the pinion 27 or 28. Assuming the parts to be in the position shown in Figure 2, the wheel 12 will rotate the pinion 27 which by means of the bevel 55 pinion 31 will operate the pinion 35 of the roller 33 in the direction to wind the advertising tape 26. Meanwhile, as the pinion 28 has been left free, the wheels 32 and 36 and with them, the roller 34 are allowed to rotate, thereby facilitating the unwinding of the tape from the last mentioned roller. When the tape or ribbon is about to arrive at its lower end, a flap 25 secured to the same, will engage with the projection 24 60 and raise the same, thereby causing the lever 65

18 to pass from the position A to the position B. This movement will cause the extension 17 to move the slide 13 and hence the beam 10 in a direction in which the wheel 12 will be made to engage with the pinion 28, whereby the direction of the circulation of the tape is reversed and will continue so till the flap of the opposite end of the tape will cause the lever 18 to return to its original position.

In this way, the reversal of the circulatory motion of the tape is effected automatically every time the same reaches one of its ends.

The lever 18 is carried to and held in one or the other of its positions by the action exerted by the roller 21 on the piece 20. One half of its stroke is performed by the trailing action of the tape, while the other half is effected by the pressure of the spring 22 and the engagement of the roller 21 with the corresponding notch or recess of the piece 20. At the moment when spring 22 is thus acting, that the cross arm 13 is caused to travel through a distance equivalent to a little more than one-half of its stroke, the remainder of its movement being caused by the engagement of the roller 15 with the corresponding recess of the piece 14.

By means of this arrangement, an instantaneous and perfect reversal is obtained.

Having now described our said invention, we declare that what we claim as new and desire to secure by Letters Patent, is:—

1. In an apparatus for operating advertising tapes, weights mounted on springs and adapted to vibrate therewith, pawls carried by the springs and engaging a ratchet wheel having a bevel gear which engages a pinion, an arm, an axle therewith extended from said pinion to an attached toothed wheel, an arm fulcrumed above said first arm adapted to move said first arm to engage said toothed wheel with a gear wheel when moved in one direction and with another gear wheel when moved in an opposite direction, arms and gear means extended from said gear wheels meshing with gears attached to rollers positioned at right angles to said arms, a curtain attached to said rollers having a flap at each end adapted to engage an extension of the fulcrumed arm.

2. In an apparatus for operating advertising tapes, springs having weights at their ends, a shaft, a ratchet wheel on the shaft, pawls on the springs engaging the ratchet wheels, an arm fulcrumed above said shaft geared at one end with the ratchet wheel and carrying a gear at its other end engageable in intermittent positions with respectively associated gears, arms and gears extended therefrom, tape carrying rollers, spindles geared with the rollers, each carrying a gear adapted to alternately mesh with the said extended gears, and means actuated by the tape for swinging said shaft to bring its gear

- into mesh with either of the gears of the spindles.
3. In an apparatus of the character described, a plurality of springs having weights at their ends, a shaft, a ratchet wheel on the shaft, pawls on the springs engaging the ratchet wheel, a swinging and counter-balanced shaft geared to the first shaft and enclosing an axle extending to a toothed wheel adapted to mesh in alternate positions with respective gears, the latter coacting by extended arms with gears adapted to propel the tape carrying rollers, means for operating the rollers from the gear wheels, a pivoted and spring pressed lever, and means on the said tape for moving the said swinging shaft by movement of said pivoted levers.
4. In an apparatus of the character described, a pair of gears to be driven, a swinging and counter-balanced shaft geared at one end to a ratchet wheel, springs having teeth engaging said ratchet wheel and oscillating weights for causing the teeth to operate the ratchet wheel, and means for swinging said shaft to bring its gear alternately into and out of mesh with the gears to be driven.
5. In an apparatus of the character described, gears to be driven, a swinging and counter-balanced shaft having a gear at one
- end for alternately meshing with the said 30 gears, springs having weights at their ends and mounted to oscillate, means for operating the shaft from the springs, a pivoted and spring pressed lever, means for swinging said shaft from its lever, and a tape holder 35 geared for alternate operation as said swinging means alternates its direction of movement.
6. In an apparatus for rotating an advertising tape in alternate directions, rollers, 40 each pivoted at one end and a gear connected at the other end, said gear connections bevel geared with further gears extended therefrom and positioned to alternately engage with a swinging counter-balanced shaft, said 45 shaft movable in alternately opposite directions by the movement of a fulcrum arm, said arm being spring pinioned in alternate positions and having an extended end engageable with flaps on the advertising tape, 50 said swinging shaft geared at one end to a ratchet wheel engaged by teeth attached to weight actuated springs.
